(57) **CLAIM**

We claim the ornamental design for a portion of a motorcycle wheel, as shown and described.

DESCRIPTION

FIG. 1 is a perspective view of a motorcycle having a wheel embodying the present invention.

FIG. 2 is an enlarged perspective view of the design shown in FIG. 1 from a different perspective than shown in FIG. 1; and,

FIG. 3 is a section view illustrating the profile of the design shown in FIG. 2.

The present application is directed to the design illustrated in the drawings. The other features of the drawings, such as the motorcycle shown in FIG. 1, are not considered part of the design sought to be patented, and have accordingly been shown in broken lines.

The design sought to be patented is not visible in the front, rear, top, or bottom views. Accordingly, these views have been omitted.
